CIGARETTE TOBACCO FEED

Charles Arelt, Richmond Hill, N. Y., assignor to
 American Machine and Foundry Company, a
 corporation of New Jersey

Application February 19, 1943, Serial No. 476,408

15 Claims. (Cl. 131—109)

I This invention relates to cigarette machines, and more particularly to mechanisms for feeding tobacco to the cigarette forming devices thereof.

It has been found that when tobacco is picked from pin rollers or fed from conveyors and allowed to fall in a shower or carpet into a chute which directs the tobacco onto the cigarette paper or web moving into the rod forming mechanisms, inequalities often result because of the non-uniform feed of tobacco into the chute. These inequalities reflect in the finished cigarettes causing differences in weights and formation of imperfect cigarettes unless some means are provided for controlling the tobacco as it is being fed to the cigarette forming mechanism. According to this invention I have provided mechanism which is operative to form and feed an extremely uniform stream of tobacco to a point where it is picked and directed onto the cigarette paper or web travelling beneath the chute into which the picked tobacco is allowed to fall so that as a result of these operations more uniform cigarettes are produced.

My invention also consists in the provision of mechanism which receives tobacco issuing from the carding rollers, and directs it in a continuous shower onto an inclined surface operative to guide it in a loose non-uniform stream between a fixed concave member and a drum having both rotary and eccentric movement so that as the tobacco is progressed from the point of entry into the restricted space between the concave and roller the tobacco stream will be densified in the direction of its travel, and converted into a stream of substantially uniform density and volume, free of holes or inequalities, whereby when the stream reaches the point of discharge, tobacco picked therefrom and showered into the tobacco delivery chute will fall in a substantially uniform carpet onto the cigarette paper or belt travelling therebeneath.

It is an object of my invention, therefore, to provide a feed for shredded tobacco or tobacco particles in which such tobacco is fed in a loose irregular stream and subjected to continuous densifying and compacting as it moves through a limited space constantly changing in width, which space is bounded by a concave and an eccentrically mounted densifier also having rotary movement within the concave whereby the stream of tobacco is converted progressively into a stream of substantially uniform density, so that as the result of the movement of the densifier relative to the concave the volume of the stream

or mat at the point of discharge from the densifying concave is substantially uniform.

It is also an object of my invention to provide a novel tobacco feeding and compacting mechanism consisting of a concave and a rotary member mounted within the concave, which member in addition to feeding tobacco as a result of its rotary movement moves rapidly to and from the concave with a rolling pin action in order to effect a lateral densifying and additional feeding movement which densifies the stream of tobacco passing between the surface of the member and the concave with the result that the tobacco is formed into a densified stream of substantially uniform volume and with the size of the shreds maintained substantially unchanged as a result of the operation of the feeding and densifying member.

It is also an object of my invention to provide a feed for shredded tobacco consisting preferably of a stationary concave and an eccentric drum mounted for compound movement in the concave whereby a loose stream of tobacco is fed, compacted and densified into a substantially uniform stream and wherein due to the operation of the drum as the tobacco stream is being compressed and densified the tobacco is allowed to expand such that the normal expansion of the compressed tobacco will insure that at all times during the movement of the tobacco stream it is engaged by both the drum and the concave.

As the densified tobacco stream travels out of the restricted passageway formed by the concave the rotating and eccentrically moving densifying and feeding drum and the end walls of the tobacco feeding mechanism, it is essential that the stream be maintained in substantially the same condition as when it leaves the passageway. That is, it is desirable that portions of the tobacco do not adhere to the drum and that little or none of the tobacco escape from the passageway into which the stream moves, otherwise the uniformity of the stream may be upset and inferior cigarettes will be formed therefrom. Due, however, to the fact that it is difficult to control properly the movement of a stream of tobacco and eliminate loss of particles as a result of the movement of the eccentrically mounted drum to and from the concave, and the mechanism forming the passageway into which the densified stream of tobacco is moved, suitable mechanism is provided for guiding and otherwise controlling the movement of the tobacco from one passageway into another.

55 It is a further object of my invention to pro-

vide a yieldingly and adjustably mounted member which has positive eccentric movement with respect to the rotating and eccentrically moving drum which forms an important part of my tobacco feeding and densifying mechanism and so locate the member that at all times it is constantly in engagement with the drum. In this manner the member performs the several functions of stripping the tobacco from the drum, applying a tamping or compacting force to the moving stream of densified tobacco and also substantially eliminates loss of tobacco from the stream of tobacco as it moves from one passageway into another.

Other objects of my invention will be set forth in the following description, it being understood that the above statement of objects is intended generally to explain the same without limiting it in any manner.

In the accompanying drawings which form a part of this specification and wherein the several reference characters designate the same or like elements:

Figure 1 is a sectional side elevation of a continuous rod cigarette machine tobacco feed embodying the invention;

Figure 2 is a front elevation, as seen from line 2—2 of Figure 1 with a partial sectional showing of inside parts;

Figure 3 is a side elevation taken on line 3—3 of Figure 2;

Figure 4 is an enlarged sectional view of a portion of Figure 1; and

Figure 5 is a sectional view taken on line 5—5 of Figure 3.

Referring to the drawings which show a preferred form of the invention selected for purposes of illustration, Figure 1 shows the general arrangement of the several cooperating elements of the cigarette machine tobacco feed consisting of a feed housing designated generally 10 in which is mounted a feed drum 11 and a refuser drum 12 which divides the interior of the feed housing into a tobacco feed chamber F and a tobacco distributing chamber D. The bottom of the feed chamber F is formed by a continuously moving endless belt 14 suitably driven by a pulley 16 in the direction indicated by the arrow. The upper lap of belt 14 runs over a guide plate 18 and an idler roller 20 which are suitably supported by side frames 22 of the tobacco feed mechanism.

The tobacco mass in feed chamber F, due to the action of belt 14, is fed towards and against the continually rotating feed drum 11 thereby filling the carded surface of this drum with tobacco. The layer of tobacco carried by the carded surface of the drum 11 is leveled off to a predetermined thickness when it passes the refuser drum 12. A picker roller 24 mounted adjacent the feed roller 11 is provided with a plurality of rows of pins 25, which pins remove the imbedded tobacco from the card clothing of the feed drum and project it into a rapidly revolving fan 26, which acting in conjunction with concentrically mounted stationary concave 28 showers tobacco onto a stationary and suitably inclined surface of a plate 30 down which the tobacco slides by gravity into a space formed between a curved portion of plate 30 and a rotating pressure roller 32. Plate 30 which is mounted on the side walls 52 of the feed housing 10 may be provided with adjustable mounts 31 having slots 33 through which project the set screws 35 in order to allow the plate to be positioned in any desired relation with respect to roller 32 and drum 36. Roller 32 pref-

erably is knurled or otherwise roughened in order to provide for a more positive engagement with the tobacco passing therebeneath. It will be seen, therefore, that the rotation of roller 32 relative to plate 30 forwards the tobacco moving down plate 30 in a more or less loose non-uniform stream, and that in this manner this stream of tobacco is directed into a passage P formed by a stationary concave 34 provided with lugs 39 and secured by screws 37 to the end walls 52 of housing 10.

Concave 34 forms a part of the tobacco stream feeding and densifying mechanism. This mechanism also includes a feeding and densifying drum 36, which preferably is provided with a roughened surface as by knurling. Drum 36, which rotates about a fixed axis centrally located with respect to concave 34, advances the stream or layer of tobacco in the restricted space formed by the inner face of the concave 34, the outer surface of the drum 36, and the end walls 52 in order to limit the travel of the stream of tobacco to a restricted passageway and prevent longitudinal expansion of the tobacco as it moves through the passageway. As the drum is rotated it also has imparted thereto a more rapid eccentric motion by which the tobacco forming the stream moving through the passageway P is subjected to a relatively large number of rapid progressive densifying impacts as the surface of the drum is moved to and from the inner face of the concave so that the tobacco is progressively compressed against the inner wall of the concave and released within the limits of the movement of the eccentric and the distance to the concave. At the same time the stream thus densified is travelled forward in passage P due to the progressive rotation of the drum. The action of drum 36 against the shredded tobacco in passage P is such that the shred size is maintained substantially unchanged as the tobacco is densified and fed through passage P. It will be evident, therefore, that the compound movement of the drum 36 relative to the inner surface of concave 34 tends to eliminate holes or voids and convert the loose irregular stream of tobacco entering passage P into a tobacco mat of substantially uniform density which is forwarded from the passage P into a passageway P' bounded by a rotating roller 38, preferably provided with a roughened surface, as by knurling, and a stationary concave 40 and end walls 52.

As the advancing edge of the uniform mat of tobacco moves beyond the limits of the passageway P' at the lower part thereof, as shown in Figures 2—4, the tobacco mat is subjected to the action of a picker 42 which separates the particles of tobacco moving into the range of action of the pins 45 carried thereby whereupon the tobacco is directed in a substantially uniform carpet onto a hurling screw 43 which advances the tobacco downwardly and in a forward direction onto the cigarette paper or conveyor 44 which is moving towards the rod forming mechanism (not shown).

Drum 36 preferably is rotated at a higher rate of speed in comparison with the rotation of drum 38 so that the tobacco stream moving through and being densified in passage P is advanced more rapidly than when the stream leaves passage P and enters passage P'. While the speed of rotation of drum 36 and roller 38 may vary within suitable limits it has been found that if drum 36 is rotated with a peripheral speed of, say three times that of roller 38, satisfactory results are obtained. The vibratory or eccentric movement of the drum can also be varied. In general

it is desired to impart a rather large number of eccentric movements to the drum in order to obtain the most favorable feeding and densifying relation with respect to the concave 34. Due to the combined operation of these members, each eccentric movement of the drum with respect to the stream of tobacco passing through the passage P, and the particular portion of the surface of the drum engaging the tobacco, results in a rolling pin like action by the drum upon the tobacco engaged. In other words, because of the rotary motion of the drum and its simultaneous movement to and from the concave the entire line of contact along the surface of the drum compacts and moves downwardly that portion of the tobacco layer momentarily engaged and at the same time the rotary motion of the drum assists further in the feed of the stream through passage P. If desired the number of eccentric motions of drum 36 per minute may be directly proportional to the rate of cigarette formation. It has been found that from 800 to 1200 oscillations per minute results in very satisfactory densifying although under some conditions higher or lower rates might be used. This combined operation results in endwise compaction of the entire stream within the limits of passageway P' and tends to assist further in the formation of a mat having substantially uniform density, and substantially unchanged shred size.

A clearing fan 46 (Figure 1) mounted and revolving close to the refuser drum 12 blows off and redirects into chamber F tobacco tending to adhere to the refuser drum. A removable stem box 50 is mounted in front of inclined plate 30. This box is slidably held by angles 51 fixed to side walls 52 positioned to catch any heavy particles or stems thrown beyond inclined plate 30 in a manner well known in the art and further description of it is deemed unnecessary.

In Figure 2 the distributing chamber is shown with part of the front wall of the feed housing 10 broken away to disclose the relative positions of the tobacco handling and feeding mechanism. As shown, the side walls 52 of housing 10 are mounted on brackets 53 suitably secured to side frames 22, which also provide bearings for the several shafts. Picker roller 24 is mounted on a shaft 54 supported in bearing 56 of bracket 53 suitably carried by one side frame 22, and the other end of shaft 54 is supported by bearing 60 of gear box 62 carried on the other side frame 22. Fan 26 is fastened to shaft 64 having one end supported by a bearing 65 and the other end mounted in a bearing 66 also formed in gear box 62. Shafts 54, 64 are driven through intermediate gearing (not shown) contained in gear box 62 by means of pulley 68, belt 70 and driving pulley 72 carried on the shaft of motor M supported on bracket 14 fixed to one of the side frames 22 (Figure 2).

Pressure roller 32 which is mounted adjacent the top end of concave 34 and coacts with inclined plate 30 in directing tobacco in a loose, irregular stream into passage P is secured to a shaft 76 supported in bearings 78, 80 fastened to side frames 22 by screws 82. A gear 84 fastened to shaft 76 by means of a screw 86 is driven continuously through an intermediate gear 88 loosely mounted on a stud 90 supported by a side frame 22, and meshing with a gear 92 coupled directly to a sprocket 94. Gear 92 and sprocket 94 are mounted loosely on stud 96. Sprocket 94 is tracked by a chain 98 running on a sprocket 100 mounted loosely on a stud 102 carried by one of the side frames 22. Sprocket 100 is directly cou-

pled to a gear 104 also mounted loosely on stud 102. Gear 104 meshes with a gear 106 fastened to the main drive shaft 108 which carries a cone pulley 110 (Figure 3) driven by a belt 111 from a suitable source of power (not shown).

The compacting drum 36 which with concave 34 and side plates 52 forms the restricted stream densifying and feeding passage P is mounted loosely on a shaft designated generally 109, which is turned down eccentrically at each end to form journal portions 113 which are held in bearings 114, 115 fastened by screws 116 to side frames 22 (Figure 2) as described hereinabove in order to impart a plurality of motions to the drum 36. Mechanism is provided for rotating the drum and simultaneously with this rotation the drum is also subjected to eccentric motion to and from the inner face of the concave 34. A preferred mechanism for operating the drum in the desired manner is shown in Figures 2, 3, and 5, although other devices may be used to accomplish the same purpose.

As illustrated in Figure 5, there is provided a flexible coupling designated generally C by means of which both rotary and eccentric movement is imparted to the drum. Secured to an end of the drum 36 by means of screws 120 is a cylindrical member 118 concentric with the axis of the eccentric portion 112 of the shaft 109 and provided with a flange 119 to the inner face of which is cemented or otherwise secured the outside face of a ring 122 of flexible or elastic material, such as rubber. The inner face of the ring 122 is secured in like manner to the outer surface of a cylindrical flanged member 124 fastened by screws 126 to a gear 128 which is concentric with the axis of the journal portions 113 of shaft 109. Gear 128 is loosely mounted for rotation on a hub formed on bracket 129 which is secured by screws 131 to a flanged portion of bearing 115, concentric with the journal portions 113 of shaft 109. On the other end of shaft 109 is fastened a pulley 130 driven by means of a belt 132 from pulley 72 on the motor M.

From the above description it is evident that the densifying drum 36 receives an eccentric motion from pulley 130 due to the eccentric portions 112 of shaft 109, and a rotary motion by means of the elastic ring 122 through its connections with the continuously driven gear 128. The resultant effect of the concurrent motions of the drum 36 on the tobacco stream moving through the passage P is the formation of a tobacco mat of substantially uniform volume.

Gear 128 meshes with a gear 128a fixed on shaft 131 mounted in a bearing 133 secured to side frame 22 (Figure 2). Also fixed to shaft 131 is a sprocket 134 which is driven continuously by means of a chain 135 from a suitable drive (not shown).

The uniform mat of tobacco resulting from the combined operations of concave 34 and drum 36 is delivered into a second passageway P' located beneath and proximate passageway P, and so constructed and arranged that the mat is maintained in substantially the same condition as it moves thereinto from passage P. In order to transfer the tobacco mat from passage P and control its movement therefrom into passage P' formed by fixed concave 40 and a rotating drum 38, which is preferably provided with a roughened tobacco engaging surface such as a knurled surface, there is provided a member 138 which acts as a guide stream compactor, and doctor blade or tobacco stripper. This member preferably extends

longitudinally along the drum 36 and is so arranged that its edge 139 is constantly in engagement with the drum regardless of the path the drum may follow during its rotation and eccentric movements. For best results it has been found that edge 139 should lie in a plane passing through the axis of the eccentric portion 112 of shaft 109. In this way edge 139 at all times follows the eccentric movement of compacting drum 36 and is in engagement with the surface in order to strip tobacco therefrom, and direct it into passage P'. Member 138 is provided with a depending portion 142 (Figures 1 and 4) preferably undercut or recessed which overlies the upper edge of concave 40 in order to provide for its proper movement relative to the drum and upper edge of the concave, eliminate any obstruction to the movement of the member 138 or impediment or stoppage in the uniform flow of tobacco from the passage P into passage P', and also act as a seal and prevent escape of tobacco between the edge of the concave and member 138 as it moves from one passage to the other. Member 138 is so formed and mounted that it exerts a yielding compacting force on the tobacco stream tending to maintain the same properly compacted as it travels from passage P into passage P'.

In the illustrated embodiment, member 138 is resiliently mounted. Referring to Figures 1-4, an angle 144 fastened to concave 40 by screws 145 extends lengthwise of the concave between the side frames 22, and mounts a number of flat springs 148 secured thereto by screws 150 and washers 152. The other ends of the springs 148 are secured to member 138 by means of screws 154 and washers 156. Member 138 has brackets 158 secured thereto at each end by means of screws 160, and fixed to brackets 158 by means of screws 162 and washers 164 are flat springs 165 which are located substantially at 90° with springs 148. These springs are also secured to lugs 166 on side frames 22 by means of screws 168 and washers 170 (Figure 4). Also connected to brackets 158 by means of screws 172 and washers 174 are flat springs 176 which are held in slots in eccentric straps 178 by means of screws 180. The eccentric straps 178 envelop portions of the shaft 112 on which the compacting drum 36 is mounted and, therefore, are constrained to follow closely the eccentric motion thereof. On the driving side of the compacting drum 36 (Figures 3 and 5), it will be seen that bracket 129 has a portion cut away as at 182 to accommodate spring 176 and its movement. Adjustments of the position of member 138 relative to drum 36 can be made in a suitable well-known manner. For instance, springs 148, 165 and 176 may be provided with longitudinal slots 151, 169 and 171 respectively in order that adjustments may be made in positioning member 138 thereon relative to drum 36.

The drum 38 is fastened to a shaft 184 mounted in bearings 186 carried by side frames 22. Each of the bearings 186 is provided with a flanged portion 187 which carries concave 40 fastened thereto by means of screws 188. Bearings 186 are fastened to side frames 22 by screws 190 in slots 192 allowing an adjustment by means of adjusting screws 193. Shaft 184 is driven from a suitable drive and source of power (not shown) by means of a chain 194 tracking a sprocket 196 fixed to shaft 184.

The constant rotary movement of concave drum 38 engaging the previously described moving tobacco mat issuing from passage P ef-

fects its movement through passage P' in order to subject the advancing edge thereof as it issues from passage P' to the action of a picker roller 42 which picks off the tobacco and throws a substantially uniform stream or carpet towards a space between a plate 200 forming a part of the feed chute and one side of a hurling screw 43, which may be of the type shown in Podmore Patent No. 1,907,575, granted May 9, 1933, which 10 imparts a forward speed to the tobacco as it falls through the chute onto the cigarette paper 44 traveling therebeneath into the rod forming mechanism of a cigarette making machine (not shown). The hurling screw 43 is journaled in 15 bearings 214 and 216 mounted on the side frames 22, and is rotated by means of a pulley 218 driven by belt 220 from pulley 72 of motor M.

Picker roller 42 is fastened to a shaft 202 mounted in bearings 204 adjustably secured to 20 side frames 22 by screws 206 (Figure 3) which allow for any necessary adjustment because of the provision of slots 208 formed in the bearings for that purpose. A belt 210 furnishes a continuous drive from pulley 72 of motor M to a 25 pulley 212 fastened to shaft 202.

In Figure 1, arrows show the general direction of rotation of the several rotating members operative in feeding tobacco and forming the substantially uniform mat. The wavy arrow applied to drum 36 illustrates substantially the motion of a random point on the surface of the drum.

The invention above described may be varied in construction within the scope of the claims, 35 for the particular device, selected to illustrate the invention, is but one of many possible concrete embodiments of the same. It is not, therefore, to be restricted to the precise details of the structure shown and described.

40 What is claimed is:

1. A tobacco feed mechanism comprising, a substantially vertically positioned stationary, concave, a roll provided with a cylindrical tobacco engaging and feeding surface coating with 45 said concave and forming therewith a restricted tobacco feeding space, means for feeding tobacco into said space between the top of said concave and roll, means mounting said roll eccentrically relative to the inner surface of said concave, 50 means for simultaneously imparting rotary and eccentric motion to said roll to move it inwardly and downwardly relative to said concave to aid in the feed of said stream through said space and densify said stream of tobacco with substantially a rolling pin action in the direction of movement in passing through said concave to a point of discharge adjacent the bottom of said concave, a doctoring device comprising a yieldingly mounted blade constructed and arranged 55 for continuous engagement with the surface of said roll located adjacent said point of discharge for directing said densified stream away from said roll, and means mounting said device for constant engagement with said roll.

60 2. In a tobacco feed mechanism, an inclined tobacco receiving surface, means for showering tobacco onto said surface, a concave, an eccentrically mounted roll located in said concave and forming with the inner surface of said concave a curved restricted tobacco feeding space, 65 means for feeding tobacco from said surface into said space, means for rotating said roll, means operative simultaneously with said last-named means for imparting eccentric motion to said roll and causing the surface thereof to move inwardly

and downwardly relative to said inner surface of said concave to feed and densify the stream of tobacco passing through said space, a second concave located beneath said roll and first-named concave, a roll to effect the feed of said densified stream of tobacco through said second concave to a point of discharge, and means for removing tobacco from the advancing end of said stream at said point of discharge.

3. In a tobacco feed mechanism, an inclined tobacco receiving surface, means for showering tobacco onto said surface, a concave, an eccentrically mounted roll located in said concave and forming with the inner surface of said concave a curved restricted tobacco feeding space, means for feeding tobacco from said surface into said space, means for rotating said roll, means operative simultaneously with said last-named means for imparting eccentric motion to said roll and causing the surface thereof to move inwardly and downwardly relative to said inner surface of said concave to feed and densify the stream of tobacco passing through said space, a second concave located beneath said roll and first-named concave, a roll to effect the feed of said densified stream of tobacco through said second concave to a point of discharge, means for removing tobacco from the advancing end of said stream at said point of discharge, a tobacco directing device comprising a doctor blade located adjacent said second concave, and means mounting said blade for constant coaction with said first named roll for directing said stream from said first named roll to said second concave, said blade including a sealing portion for preventing escape of tobacco between said second concave and blade.

4. In a tobacco feed mechanism, a concave, a rotary drum mounted within said concave and forming therewith a restricted space for the passage of tobacco between said concave and drum, means mounting said drum eccentrically within said concave, mechanism for feeding a loose stream of tobacco into said space bounded by said concave and the surface of said drum, means for simultaneously imparting rotary and eccentric motion to said drum to effect the feed of said stream of tobacco and densify said stream as it is fed to a point of discharge, a second concave mounted beneath said drum, a roller mounted within said second concave, forming with said second concave a stream feeding passage, and means located between said drum and second concave for maintaining said stream compacted and directing the same from said first concave into said second concave.

5. In a tobacco feed mechanism, a concave, a rotary drum mounted within said concave and forming therewith a restricted space for the passage of tobacco between said concave and drum, means mounting said drum eccentrically within said concave, mechanism for feeding a loose stream of tobacco into said space bounded by said concave and the surface of said drum, means for simultaneously imparting rotary and eccentric motion to said drum to effect the feed of said stream of tobacco and densify said stream as it is fed to a point of discharge, a second concave mounted beneath said drum, a roller mounted within said second concave and forming with said second concave a stream feeding passage, a doctor blade located between said drum and second concave for directing said densified stream of tobacco from said first concave into said second concave, and yielding means mounting said blade

for continuous engagement with said drum during rotation thereof.

6. In a tobacco feed, a concave, a feeding drum spaced from said concave and forming therewith a tobacco passage, means for feeding a stream of loose tobacco to said passage, means for rotating said drum at one rate of speed, means for simultaneously oscillating said drum at a rate greater than the rotary movement of said drum for feeding said stream of tobacco and densifying the same as it travels through said passage, a second feeding passage located below said first-named passage, means for progressing said densified stream at a slower rate of movement through said second passage in a substantially uninterrupted stream, and means for separating tobacco from said stream as it issues from said second passage.

7. In a tobacco feed, a concave, a feeding drum spaced from said concave and forming therewith a tobacco passage, means for feeding a stream of loose tobacco to said passage, means for rotating said drum at one rate of speed, means for simultaneously oscillating said drum at a rate greater than the rotary movement of said drum for feeding said stream of tobacco and densifying the same as it travels through said passage, a second feeding passage located below said first-named passage, a guide member located adjacent said drum proximate said first and second passages, means for progressing said densified stream at a slower rate of movement through said second passage, and means for separating tobacco from said stream as it issues from said second passage.

8. In a tobacco feed, a concave, a feeding drum spaced from said concave and forming therewith a tobacco passage, means for feeding a stream of loose tobacco to said passage, means for rotating said drum at one rate of speed, means for simultaneously oscillating said drum at a rate greater than the rotary movement of said drum for feeding said stream of tobacco and densifying the same as it travels through said passage, a second feeding passage located below said first-named passage, a resiliently mounted guide member located proximate said first and second passages, means mounting said member for constant engagement with said drum, means for progressing said densified stream at a slower rate of movement through said second passage, and means for separating tobacco from said stream as it issues from said second passage.

9. In a tobacco feed mechanism, a shaft provided with an eccentric portion and end journals, a drum loosely mounted on said eccentric portion, a stationary concave spaced from said drum and forming with said drum a curved tobacco feeding passage having a tobacco stream receiving opening for receiving a stream of loose non-uniform pieces of tobacco, and a discharge opening delivering a densified substantially uniform stream of tobacco, means for feeding a loose stream of tobacco to said receiving opening comprising an inclined plate, a roller spaced therefrom mounted adjacent the top of said concave, and means for showering tobacco upon said plate for delivery by said plate and roller to said receiving opening of said passage between said drum and concave, mechanism for imparting a plurality of compound movements to said drum relative to said stationary concave to feed said loose stream through said passage and densify the same in the direction of its travel as it moves therethrough to said discharge opening while maintaining the size of said pieces of tobacco

11

substantially unchanged, said mechanism including driving means for rotating said shaft, a flexible coupling connected to one end of said drum, and means driving said coupling for rotating said drum on said shaft simultaneously with the independent rotation of said shaft.

10. In a tobacco feed mechanism, an eccentrically mounted drum, a concave spaced from said drum and forming with said drum a curved tobacco feeding passage having a tobacco stream receiving opening for receiving a stream of loose non-uniform tobacco, and a discharge opening delivering a densified substantially uniform stream of tobacco, means for feeding a loose stream of tobacco to said receiving opening comprising an inclined plate, a roller spaced therefrom, and means for showering tobacco upon said plate for delivery by said plate and roller to said receiving opening, mechanism for imparting a plurality of compound movements to said drum relative to said concave to feed said loose stream through said passage and densify the same in the direction of its travel as it moves therethrough to said discharge opening, a concave and a roller located adjacent said discharge opening and forming a second passage for said densified stream, and means for driving said last-mentioned roller at a slower rate of speed than said drum to travel said densified stream through said second passage more slowly than through said first passage.

11. In a tobacco feed mechanism, an eccentrically mounted drum, a concave spaced from said drum and forming with said drum a curved tobacco feeding passage having a tobacco stream receiving opening for receiving a stream of loose non-uniform tobacco, and a discharge opening delivering a densified substantially uniform stream of tobacco, means for feeding a loose stream of tobacco to said receiving opening comprising an inclined plate, a roller spaced therefrom, and means for showering tobacco upon said plate for delivery by said plate and roller to said receiving opening, mechanism for imparting a plurality of compound movements to said drum relative to said concave to feed said loose stream through said passage and densify the same in the direction of its travel as it moves therethrough to said discharge opening, a concave and a roller located adjacent said discharge opening and forming a second passage for said densified stream, means for driving said last-mentioned roller at a slower rate of speed than said drum to travel said densified stream through said second passage more slowly than through said first passage, a chute beneath said second passage, and means for separating tobacco from said stream as it issues from said second passage and delivering the same to said chute.

12. In a tobacco feed mechanism, spaced members forming a tobacco feeding zone comprising a concave, and a drum within said concave, means for feeding a loose stream of tobacco into said zone, a second tobacco feeding zone beneath said first feeding zone comprising a second concave and a roller spaced therefrom, means for imparting rotary and eccentric motion to said drum at one speed to feed said stream of tobacco into said second feeding zone, means for rotating said roller at a slower rate of speed relative to the speed of said drum to control the passage of said stream through said second zone, a doctor blade, and means for constantly engaging said blade with said drum to direct tobacco passing from said first zone in a substantially

12

continuous unbroken stream into said second zone.

13. In a tobacco feeding mechanism, an eccentrically mounted drum, a concave spaced therefrom and forming therewith a tobacco feeding passage, means for feeding tobacco into said passage, mechanism for rotating said drum and for simultaneously causing said drum to move to and from the inner surface of said concave and densify tobacco in said passage and feed said densified tobacco to a point of discharge, a doctor blade extending lengthwise of said drum, a support for said doctor blade, and adjustably mounted springs mounting said blade on said support and constructed and arranged to locate the edge of said doctor blade in constant engagement with said drum.

14. In a tobacco feeding mechanism, spaced members forming a tobacco feeding zone comprising a stationary concave and a tobacco feeding member, means for feeding a loose stream of tobacco into said zone, means for imparting rotary and oscillating motion to said feeding member, a second tobacco feeding zone beneath said first feeding zone comprising a second concave and a second feeding member spaced therefrom, a movable doctoring device located in the space between said first-named tobacco feeding member and said second-named concave, said doctoring device being constructed and arranged to form with said tobacco feeding members and said second-named concave a substantially continuous tobacco passage connecting said first and second tobacco feeding zones, means mounting said doctoring device for constant engagement with said first-named feeding member, and means on said movable doctoring device for substantially preventing escape of tobacco from said passage.

15. A tobacco feed mechanism for a cigarette machine comprising a substantially semicircular stationary concave having a top infeed end and a bottom discharge end, means mounting said concave with said top end located above said bottom end, feeding means provided with a cylindrical surface mounted within said concave and forming with the entire inner face thereof a continuously open restricted substantially semicircular tobacco passage, means for moving said feeding means with a circular motion in feeding a tobacco stream through said passage, and means operative simultaneously therewith for also imparting eccentric motion to said feeding means to cause the cylindrical surface at an entire line of contact along the length thereof to compact and move downwardly a substantial portion of the tobacco stream in said passage engaged by said surface at that line for densifying said stream as it moves through said passage to form a substantially uniform stream for discharge from said passage, said cylindrical surface being constructed and arranged to maintain the size of said shreds of compacted tobacco substantially unchanged during the movement thereof through and out of said passage.
